MOTORCYCLE WHEEL

William G. Davidson, Elm Grove, Wis., assignor to
AMF Incorporated

Filed Oct. 30, 1970, Ser. No. 25,727

Term of patent 14 years

Int. Cl. D12—16

U.S. Cl. D14—30

FIG. 1

FIG. 2

FIG. 1 is a side elevation view of a motorcycle wheel incorporating my design; and

FIG. 2 is a sectional view taken along the section line 2—2 of FIG. 1.

The wheel is cast metal which is polished on the outer surfaces.

I claim:

The ornamental design for a motorcycle wheel, as shown and described.
